UNITED STATES PATENT OFFICE.

EDWARDS RUSSELL FISH, OF PHOENIXVILLE, PENNSYLVANIA.

SUPERHEATED-STEAM BOILER.

1,350,597.

Specification of Letters Patent. Patented Aug. 24, 1920.

Application filed August 20, 1918. Serial No. 250,661.

To all whom it may concern:

Be it known that I, EDWARDS RUSSELL FISH, a citizen of the United States, residing at Phoenixville, in the county of Chester and State of Pennsylvania, have invented certain new and useful Improvements in Superheated-Steam Boilers, of which the following is a specification.

One object of my invention is to provide a superheated steam boiler in which the superheater will have portions so located that they will deliver a comparatively large amount of superheated steam and at the same time will be located in such a position as to permit easy access thereto for cleaning or repair purposes.

Another object is to so construct and locate the superheater that any of the tubes can be easily and quickly repaired or replaced without removing the entire superheater or any other part thereof.

A further object is to so make my improved boiler and superheater that the tubes of the latter can straddle certain of the parts of the boiler, thus permitting the superheater to be installed without greatly increasing the space required by the boiler proper.

These objects, and other advantageous ends which will be described hereinafter, I attain in the following manner, reference being had to the accompanying drawings in which—

Figure 1 is a sectional elevation taken longitudinally through my improved boiler,

Fig. 2 is a transverse sectional elevation taken on the line 2—2 of Fig. 1,

Fig. 3 is a section through the superheater header taken on the line 3—3 of Fig. 2,

Fig. 4 is a fragmentary section taken on the line 4—4 of Fig. 3, through the superheater header and showing the arrangement of the superheater tubes with relation to the baffles in the superheater header,

Fig. 5 is a view of the same general character as Fig. 2, showing a modified form of superheater arrangement and made in accordance with my invention,

Figs. 6, 7, and 8 are fragmentary views of the same general character to Figs. 2 and 5 and showing certain other modified forms of the superheater arrangement and made in accordance with my invention, Fig. 8 being a section taken on the line 8—8 of Fig. 9, and

Fig. 9 is a transverse sectional view taken on the line 9—9 of Fig. 8.

Referring to Figs. 1 to 4, inclusive, of the drawings, 5 represents the boiler casing, 6 represents the combustion chamber or fire box, and 7 represents the grates. 8 and 9 respectively represent the front and rear water tube headers which are connected by an inclined bank of water tubes 10. These tubes extend over the fire box 6 and the heat from the latter serves to generate steam within the tubes 10 which passes rearwardly to the box header 9 and thence through a row of steam conducting tubes 11 to a steam and water drum 12. The latter is arranged transversely of the boiler and is connected by nipples 13 with the top of the front header 8. The steam conducting tubes 11 extend at an angle to the tubes 10 and thus provide a substantially triangular space 14 between the uppermost tubes 10 and the tubes 11.

The tubes 10 are provided with baffles 15, 16, and 17 and the hot products of combustion are thus compelled to take a circuitous path, as indicated by the arrows in Fig. 1, upwardly between the water tubes so as to efficiently heat them to produce steam and then pass into the space 14 and eventually out of a flue outlet 18 in the top of the casing 5.

As illustrated, the baffle 15 is located between the front and rear headers 8 and 9 so as to provide passageways 19 and 20 at opposite ends so that a part of the products of combustion, after passing around the baffle 16, is free to pass into the space 14 through both of the passageways 19 and 20.

Another baffle 21 is provided above the tubes 11, as clearly shown in Figs. 1 and 2, and this baffle has portions adjacent the drum 12 and also adjacent and leading to the rear baffle 9. However, this baffle is discontinued within its length to provide an opening 22 for the products of combustion so that they may pass upwardly from the space 14 between the tubes 11 prior to passing out of the flue outlet 18.

A superheater 23 is mounted in the upper portion of the casing 5 and includes a rectangular box header 24. This superheater header is mounted in one side of the casing 5 and at such height that the top and bottom of the superheater header 24 are respectively above and below a horizontal plane includ-

ing the boiler tubes 11, as clearly shown in Fig. 1. In other words, a part of the superheater header 24 is located at a lower level than the tubes 11 and another portion of the 5 superheater header 24 is positioned above the level of the tubes 11.

An inlet steam pipe 25 communicates with the steam and water drum 12 and with the superheater header 24, the connection of said 10 steam pipe 25 with the superheater header being at a level above the tubes 11. Thus steam passes from the drum 12, through the pipe 25 into the top portion of the superheater header 24.

15 A superheated steam take-off pipe 26 leads from the superheater header 24 at a position below the level of the tubes 11 and the superheated steam generated, in a manner hereinafter described, will be delivered 20 through the pipe 26.

25 A series 27 of superheater tubes are arranged in two groups 28 and 29. The tubes of each of these groups are each bent in elongated U-shape form, the open ends of each tube being secured within the superheater header 24 so as to communicate therewith. The superheater header 24 is provided, in the present instance, with two 30 baffles 30 and 31 which form partitions which are spaced apart so as to produce three separate chambers 32, 33, and 34.

35 The chambers 32 and 34 are respectively adjacent the top and the bottom of the header 24 while the chamber 33 is centrally disposed. The inlet steam pipe 25 communicates with the chamber 32. The take-off or outlet pipe 26 for the superheated steam communicates with the chamber 34.

40 The upper leg portions or runs 35 of each of the tubes of the group 28 communicate with the chamber 32 while the lower leg portions or runs 36 of the tubes of said group 28 communicate with the chamber 33. On the other hand, the upper leg portions 45 or runs 37 of the tubes of the group 29 communicate with the chamber 33 while the lower leg portions or runs 38 of the tubes of said group 29 communicate with the chamber 34 so that it will be understood 50 that steam passing into the chamber 32 will pass through the upper runs 35, then through the lower runs 36 into the chamber 33, then out of the chamber 33 through the upper runs 37 of the group of tubes 29, and then through the lower runs of said latter tubes into the chamber 34 thus producing a circulation of the steam while being superheated.

55 The tubes of both of the groups 28 and 29 are arranged in alinement with the opening 22 of the baffle 21. The groups of tubes 28 are spaced above the group 29, as clearly indicated at 39, and this permits the groups 28 and 29 to span the tubes 11. Thus the 60 group 29 can be conveniently located within

the space 14 below the tubes 11, while the group 28 will be positioned above the tubes 11. Furthermore, the tubes of each group 28 and 29 are arranged in staggered formation, as clearly shown in Figs. 1, 2, and 3, 70 so that the products of combustion can pass between the bends of all of the superheater tubes.

75 Also, the corresponding tubes of each group are preferably positioned in direct vertical alinement with each other. Thus if any of the tubes of the groups 28 and 29 are in need of repair or replacement, it is an easy matter to cut the tube from the header and replace the same. The superheater thus made and arranged will absorb a comparatively large amount of heat and it is an easy matter to insert or remove the superheater as a unit since it is arranged at the top of the boiler casing, and it can be 80 merely slid into position after the elements of the boiler structure are assembled.

85 By having the superheater tubes arranged in groups so that they will straddle the tubes 11, a portion of the superheater tubes 90 are actually between the elements of the boiler proper and thus receive a large amount of heat.

95 In the form of my invention illustrated in Fig. 5 instead of having the superheater header as above described I form the superheater header 40 in three separate sections, there being a central section 41, a top section 42, and a bottom section 43. The two groups 44 and 45 of superheater tubes are 100 respectively arranged above and below the steam conducting pipes 11.

105 The superheater tubes 44 and 45 are U-shape in construction similar to those above described, and one leg of each tube of the superheater tubes communicates with the central section 41 of the superheater header. In other words, the superheater header section 41 is in communication with both of the groups 44 and 45. The other legs of said 110 superheater tubes respectively connect with the sections 42 and 43 of the superheater header 40.

115 The steam and water drum 12 delivers its steam into the section 42 of the superheater header 40 by means of a pipe 46 and the section 43 of the superheater header has an outlet pipe 47 for taking off the superheated steam.

120 In the form of my invention shown in Fig. 6, I provide a single superheater header 48 which is divided into two compartments 49 and 50 by means of a partition or baffle 51. The superheater tubes 52 are U-shape as illustrated and have their open ends respectively communicating with the compartments 49 and 50 of the superheater header 48; the arrangement being such that the run 53 of the superheater tubes is positioned 125 above the steam conducting pipes 11 and the 130

run 54 of the superheater tubes is below the steam conducting pipes 11. With this arrangement a steam pipe 55 conducts the steam from the steam and water drum 12 to the compartment 49 of the superheater header 48 and a superheated steam take-off pipe 56 communicates with the compartment 50.

The construction shown in Fig. 7 is substantially similar to that described in connection with Fig. 6 with the exception that instead of having a single superheater header the superheater header in Fig. 7 consists of two separate parts 57 and 58. The superheater tubes 59 have their upper and lower runs spanning the steam conducting pipes 11 in the same manner as described in connection with Fig. 6. The upper run communicates with the superheater header section 57, while the lower run of the superheater tubes communicates with the superheater header section 58. In this construction the steam from the steam and water drum 12 passes into the superheater header section 57 through a pipe 60. A take-off pipe 61 for the superheated steam communicates with the superheater header section 58.

In Figs. 8 and 9 I have shown an arrangement of my invention in which two rows of steam conducting tubes 11^a and 11^b are provided so as to illustrate that my invention can be constructed on boilers having different numbers of steam conducting pipes between the rear water tube headers and the steam and water drum.

Instead of having the superheater tubes in the arrangement, for example, as shown in Fig. 1, I have angularly disposed these tubes, as clearly shown in Fig. 9. In all other respects the construction illustrated in Figs. 8 and 9 is similar to that described in connection with Figs. 1 to 4, inclusive, and I have therefore given corresponding parts similar reference numerals.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A superheated steam boiler including a superheater having a plurality of groups of tubes, the groups being spaced apart and transversely spanning a portion of the boiler proper whereby said tubes occupy spaces at opposite sides of said portion of the boiler, and a header for said groups of tubes extending into the boiler setting whereby the tubes and header can be freely

removed as a whole from the boiler, substantially as described.

2. A superheated steam boiler including a superheater having a header extending into the boiler setting; and a plurality of groups of superheater tubes communicating with said header, said groups being spaced apart and spanning transversely a portion of the boiler proper whereby the groups of superheater tubes occupy spaces at either side of said boiler portion, substantially as described.

3. A superheated steam boiler including a bank of water tubes; other tubes extending at an angle to said first mentioned tubes whereby a space is provided; a flue outlet being provided above said second mentioned tubes; and a superheater having groups of superheater tubes spaced apart and spanning said second mentioned tubes whereby certain of said groups of tubes are positioned within said first space and others of said groups are positioned between said second mentioned tubes and said flue outlet, substantially as described.

4. A superheated steam boiler having front and rear headers; a bank of water tubes connecting said headers; a steam and water drum; means communicating with said drum and one of said headers; tubes extending at an angle to said first tubes and communicating with said drum and the other of said headers whereby a space is provided between said first and second mentioned tubes; means providing a flue outlet above said second mentioned tubes; a superheater header; and a series of superheater tubes arranged in groups spaced apart and communicating with said superheater header, said groups spanning said second mentioned tubes whereby certain of the groups of tubes are positioned within said first space and the others of said groups of tubes are positioned between said second tubes and the flue outlet, substantially as described.

5. A superheated steam boiler having front and rear headers; a bank of water tubes connecting said headers; a steam and water drum; means communicating with said drum and one of said headers; tubes extending at an angle to said first tubes and communicating with said drum and the other of said headers whereby a space is provided between said first and second mentioned tubes; means providing a flue outlet above said second mentioned tubes; a superheater header; a series of U-shape tubes arranged in groups and having their open ends communicating with said superheater header; and means within said superheater header positioned to form a circulation of steam, first through the tubes of one group and then through the tubes of another group, said groups of tubes being spaced apart and spanning said second mentioned tubes.

tubes whereby certain of the groups of tubes are positioned within said first space and the others of said groups of tubes are positioned between said second tubes and the flue outlet, substantially as described.

6. A superheated steam boiler having front and rear headers; a bank of water tubes connecting said headers; a steam and water drum; means communicating with said drum and one of said headers; tubes extending at an angle to said first tubes and communicating with said drum and the other of said headers whereby a space is provided between said first and second mentioned tubes; means providing a flue outlet above said second mentioned tubes; a superheater header; a series of U-shape tubes arranged in groups and having their open ends communicating with said superheater header; and means within said superheater header positioned to form a circulation of steam, first through the tubes of one group and then through the tubes of another group, said groups of tubes being spaced apart and spanning said second mentioned tubes whereby certain of the groups of tubes are positioned within said first space and the others of said groups of tubes are positioned between said second tubes and the flue outlet, the tubes of each group being arranged in a staggered formation for permitting a free circulation of the products of combustion therebetween, substantially as described.

7. A superheated steam boiler including a superheater having a header extending

through the boiler setting and a plurality of groups of superheater tubes communicating with said header, said groups being spaced apart one above another and transversely spanning within their heights a portion of the boiler proper whereby the groups of superheater tubes occupy spaces at either side of said boiler portion and the header and superheater tubes can be freely removed as a whole from the boiler; substantially as described.

8. A superheated steam boiler including a bank of water tubes; other tubes extending at an incline to said first mentioned tubes, whereby a space is provided; a flue outlet being provided above said second mentioned tubes and a superheater having tubes, a portion of said superheater tubes being mounted below said second mentioned tubes and another portion of said tubes being mounted above said second mentioned tubes whereby said first portion of the superheater tubes are positioned within said first space and the second mentioned portion of the superheater tubes are positioned between said second mentioned tubes and said flue outlet; substantially as described.

In testimony whereof I have signed my name to this specification in the presence of two subscribing witnesses.

EDWARDS RUSSELL FISH.
